KLARA SCHULTZ, OF BROOKLYN, NEW YORK

CATAMENIAL BELT

Application filed February 21, 1928. Serial No. 255,897.

This invention relates to improvements in catamenial belts, and has for one of its objects to provide an improved belt of simple and practical construction which may be readily attached in position and form a comfortable support for a napkin.

Another object is to provide an improved attaching means for the napkin by means of which the same may be quickly secured in proper position and retained therein while being worn.

The above and other objects will appear more clearly from the following detailed description, when taken in connection with the accompanying drawing, which illustrates a preferred embodiment of the invention idea.

In the drawing—

Figure 1 is a perspective view of the belt constructed in accordance with the invention; 20 Figure 2 is a plan view of the napkin supporting means;

Figure 3 is a longitudinal section therethrough; and

Figure 4 is a fragmentary front elevation. 25 Referring more particularly to the accompanying drawing, 5 indicates a girdle of elastic material adapted to partially encircle the waist and having attached to each end a tape 6, the free ends of said tapes being tied together to support the girdle in position.

The girdle further has attached thereto, preferably adjacent its ends, the downwardly converging supporting bands 7, also of elastic material.

35 The belt further comprises a napkin-supporting member including a back section 8 of fabric secured at one end to the girdle, and a front section 9 of rubber or similar material attached to said back section. The supporting member tapers gradually toward the front end and said section 9 at its forward extremity is gathered as indicated at 10 to form, in effect, a shallow pocket 11 for a purpose which will presently appear. The front end 40 of the section 9 is permanently held in its gathered condition by a folded strip of fabric 12 having its folds arranged on opposite sides of said end and stitched or otherwise secured thereto. Double-headed studs 13 are mounted 45 in and extended through the strip 12 and

end of the section 9 with the outer heads of said studs utilized as attaching means for the lower ends of bands 7. To the inner heads of the studs may be attached the loops 14 of an absorbent body 15, such as a sponge, which is adapted to be supported by said loops in the pocket 11, as best shown in Figure 3.

On the exterior side of the strip 12 and intermediate its ends there is provided a hook 16 to which is adapted to be attached one end of the napkin 17 to secure said end in position. The napkin lies upon the section 9 of the supporting member, covering the absorbent body 15 which cooperates with said napkin as an absorbent medium, and has its rear end held in position by an elastic strip 18 under which said end is inserted and which extends transversely of the section 9 adjacent the point of attachment thereof to the section 8. In order to maintain the sections 8 and 9 in relatively flat condition adjacent their meeting ends and to prevent transverse contraction thereof under the influence of the strip 18, there is secured in the supporting member, transversely thereof and contiguous to the said strip, a flexible but relatively stiff rib 19 of whalebone or similar material.

What is claimed is:

45 A catamenial belt including a belt member, a supporting member attached at one end to said belt member, an impaling element permanently attached to the outside of said supporting member adjacent the free end thereof, means for attaching the front end of said supporting member to said belt, an elastic strip extending transversely of said supporting member at a point removed from said impaling element, and a flexible stiffening rib secured to the supporting member adjacent said strip, whereby a napkin may be quickly attached to said supporting member and held in flat condition by said elastic strip.

In testimony whereof I have affixed my signature.

KLARA SCHULTZ.
